(57) **CLAIM**

The ornamental design for a bath filler, as shown and described.

DESCRIPTION

FIG. 1 is a perspective view of the claimed design; FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The ornamental design that is claimed is shown in the drawings as solid lines and surfaces having surface shading. The broken lines formed by equal length dashes show portions of the design that form no part of the claim. The broken lines formed of dash-dot lengths show boundaries of the claim.

1 Claim, 4 Drawing Sheets
